UNITED STATES PATENT OFFICE

149,088

DESIGN FOR AN X-RAY SHOE FITTING
CABINET

Jean Otis Reinecke, Oak Park, Ill., assignor to
Primex Equipment Company, Chicago, Ill., a
corporation of Illinois

Application October 5, 1946, Serial No. 133,796

Term of patent 14 years

(CL. D83—1)

To all whom it may concern:

Be it known that I, Jean Otis Reinecke, a citizen of the United States, residing at Oak Park, in the county of Cook and State of Illinois, have invented a new, original, and ornamental Design for an X-Ray Shoe Fitting Cabinet, of which the following is a specification, reference being had to the accompanying drawing, forming a part thereof.

Fig. 1 is a perspective view showing the top, front, and one side of an X-ray shoe fitting cabinet embodying my new design;

Fig. 2 is a rear perspective view of the cabinet showing the top, back, and one side thereof, with the top door panel shown in open position revealing a control switch panel; and

Fig. 3 is a rear perspective view of the cabinet with the top door panel shown in closed position.

I claim:

The ornamental design for an X-ray shoe fitting cabinet, as shown.

JEAN OTIS REINECKE.
